UNITED STATES PATENT OFFICE.

SAMUEL GRAVES, OF NORTH WEYMOUTH, MASSACHUSETTS.

LOUNGE-BED.

SPECIFICATION forming part of Letters Patent No. 230,545, dated July 27, 1880.

Application filed June 30, 1879.

To all whom it may concern:

Be it known that I, SAMUEL GRAVES, a resident of North Weymouth, in the county of Norfolk and State of Massachusetts, have invented certain new and useful Improvements 5 in Convertible Sofas or Lounges, commonly termed "Lounge-Beds;" and I do hereby declare that the following is a full, clear, and exact description of the invention, which will 10 enable others skilled in the art to which it appertains to make and use the same, reference being had to the accompanying drawings, and to letters of reference marked thereon, which form a part of this specification.

15 This invention relates to that type of lounges which are so constructed that when required they can be widened and turned into a bed, the legs and head and foot boards being placed in recesses formed for their reception when 20 the device is being used as a lounge; and it consists in certain combinations and arrangements of the parts of which it is composed, which are designed to facilitate the changing of the positions of the parts in converting it 25 from a lounge to a bed, as hereinafter more fully described and claimed.

The description and operation of my invention will be fully explained hereinafter.

In the annexed drawings, making a part of 30 this specification, Figure 1 is a longitudinal vertical section of the device when used as a lounge, showing the manner of storing the head-board when not in use. Fig. 2 is a perspective view of the lounge with the top thrown up to allow the extension to be opened, also 35 showing the foot-board when not in use. Fig. 3 is a perspective view of the lounge when opened out for use as a bed, the head and foot boards being adjusted. Fig. 4 is a longitudinal vertical section of the extension, showing 40 the mode of adjusting the legs. Fig. 5 is a plan view of the back of the lounge. Fig. 6 is a perspective view of the foot-board. Fig. 7 is perspective view of the lug used for attaching the back to the body of the lounge. Fig. 8 is a perspective view of the stirrup in 45 which the lug shown in Fig. 7 rests.

The same letters are employed in all the figures in the indication of identical parts.

50 The bed portion of lounge consists of three

parts or sections, A, B, and C, the two former being hinged together, preferably at the head, by means of the hinges A' A', so that the upper section can be tilted up into the position shown in Fig. 2, to admit of the opening of 55 the hinged extension part C.

The hinging of the part A at its end, so as to cause it in being tilted to assume a vertical position, forms an important feature of my invention, as it enables the change from a lounge 60 to a bed to be made in a room the width of which is not sufficient to allow it to be turned horizontally, and it also renders it more convenient to arrange the bedding upon the part C when it has been turned into a position to 65 receive it. This extension rests in the lower section of the body, and is hinged to the rear side rail of it, upon which hinges it swings when turned back to form a bed. The cross-pieces of this frame are grooved, said grooves 70 being covered with slotted plates D D, to receive the headed bolts E' E', attached to the legs E E, and hold them in place. After the legs have been adjusted, the buttons F F, attached to the frame C near the slotted plates, 75 are turned, thus preventing the legs from falling out while the frame is being turned back or while being moved about the room, the extension being down.

G is the head-board, formed with projections 80 or lugs, which, when not in use, is held in a recess formed in the arm H of the lounge, behind the cross-piece H', and can only be removed when the upper section, A, is tilted up; but when required for use the lugs enter an 85 inclined recess, I, in the extension, forming a head-board for it.

K is the foot-board, constructed, as shown, with two swinging arms, K' K', which shut up into recesses in the foot-piece, like the blades of 90 a knife, as indicated in dotted lines in Fig. 6, so that when not in use the board may be placed between the frame C and the front side of the section B. When required for use the swinging arms are opened and enter slots in the extension near the foot.

L is the back of the lounge, and is provided with lugs m m and stirrup n, which, when the back is in place, engage corresponding stirrups O and lug P on the back of the body B 100

and arm H, forming dovetails, which securely hold the back in position.

The device being used a lounge and it is desired to convert it into a bed, the operation is 5 as follows: Remove the back and turn the upper section on end; remove the legs, head and foot boards and adjust the legs to the extension, turning the buttons against them, and turn it back until the legs rest on the floor; 10 then lower the top section and adjust the head and foot boards.

I am aware that convertible lounges have heretofore been patented; but my invention 15 is distinguished from those in the manner of extending and of disposing of the head and foot boards.

What I claim as my invention, and desire to secure by Letters Patent, is—

1. In a lounge or sofa designed to be converted into a bed at pleasure, the combination 20

of the hinged portions A and C with the fixed portion B, the portion A being hinged to B at its end, substantially as and for the purpose set forth.

2. The combination, in a lounge-bed, of the 25 swinging portion A, the hinged extension part C, having in it an inclined recess for the reception of a removable head-board, the fixed portion B, to which the parts A and C are hinged, and a removable head-board fitted to 30 slide in the inclined recess I in the portion C, the parts being constructed and arranged for operation as described.

In testimony that I claim the foregoing as my own I affix my signature in presence of two 35 witnesses.

SAMUEL GRAVES.
